Fig. 4

Fig. 5

Figure 1 is a left side elevational view of a self-propelled combine embodying my new design.

Figure 2 is a plan view of the combine shown in Figure 1, but showing a part broken away for convenience of illustration.

Figure 3 is a front elevational view of the combine shown in Figures 1 and 2.

Figure 4 is a perspective view of the combine shown in the other figures, taken generally from the right, rear side thereof; but on a smaller scale.

Figure 5 is a perspective view of the combine shown

in Figure 4, taken generally from the left, rear side of the combine.

The dominant features of the design reside in the portions shown in full lines.

I claim:

The ornamental design for a self-propelled combine, substantially as shown and described.
